DESIGN FOR A SCOOTER

Joseph M. Rodriguez, Brooklyn, N. Y.

Application May 29, 1940, Serial No. 92,686

Term of patent 14 years

To all whom it may concern:

Be it known that I, Joseph M. Rodriguez, a citizen of the United States, residing at Brooklyn, in the county of Kings and State of New York, have invented a new, original, and ornamental Design for a Scooter, of which the following is a specification, reference being had to the accompanying drawing, forming part thereof.

Fig. 1 is an isometric perspective view of a scooter, showing my new design;

Fig. 2 is a front elevational view thereof;

Fig. 3 is an enlarged transverse sectional view taken on line 3—3 of Fig. 2.

I claim:

The ornamental design for a scooter, as shown.

JOSEPH M. RODRIGUEZ.
